UNITED STATES PATENT OFFICE

HARRY J. SMITH, OF LAKWOOD, OHIO

AGITATOR

Application filed December 8, 1927. Serial No. 238,665.

This invention relates to an agitator which is more particularly designed for mixing liquids such as paint, paper pulp, cement, slurry, chemicals, and the like, and which depends for its operation on the principle of the Venturi tube.

Agitation of liquids for mixing them in a tank has heretofore been more or less haphazard, inefficient and unsatisfactory. Production of turbulence in the liquid by mechanical stirring has been a fundamental method of mixing the same. But usually such stirring is only of a local nature and a real mixture of the entire mass is rarely, if ever, attained. The same condition results from the use of air introduced under pressure into the liquid and passing through the same in the form of bubbles, no homogeneous mixing of the liquid being possible.

20 The object of this invention is the provision of an agitator whereby the entire mass of liquid will be mixed thoroughly, homogeneously and quickly with a minimum expenditure of power.

25 To that end this invention contemplates to use a Venturi tube in its organization in which a distinct circulation of the entire volume of liquid is obtained and all parts of the same are intimately mixed.

30 In the accompanying drawings:

Figure 1 is a vertical section of one form of Venturi tube agitator embodying my invention. Figure 2 is a top plan view thereof. Figures 3 and 4 are horizontal sections taken on the correspondingly numbered lines in Fig. 1. Figure 5 is a fragmentary vertical section taken on line 5-5, Fig. 2. Figure 6 is a fragmentary side elevation of the means for raising and lowering the vertically movable part of the Venturi tube shown in Fig. 1. Figure 7 is a vertical section of another form of my improvement. Figure 8 is a horizontal section taken on line 8-8, Fig. 7. Figure 9 is a fragmentary vertical section of the lower part of the tank and the Venturi tube showing another modification of my invention. Figures 10, 11, 12 and 13 are diagrammatic views in vertical section, side elevation, top plan and bottom plan showing the action of the liquid currents during the op-

eration of my improved agitator. Figure 14 is a vertical longitudinal section of a form of apparatus embodying my invention in which the Venturi tube is arranged horizontally.

In the following description similar characters of reference indicate like parts in the several figures of the drawings.

Referring to Figs. 1-6, the numeral 20 represents an upright tank which is adapted to hold the charge of liquid to be mixed and which may be constructed of any material to suit the character of the liquid under treatment. The liquid may be introduced into the top of the tank at the top and withdrawn from the bottom thereof through a pipe 21 having a suitable valve for controlling the same.

The means whereby the mixing of the liquid is effected in accordance with my invention are constructed as follows:

Arranged vertically within the central part of the tank is a Venturi tube which has a reduced or contracted throat 22 between its upper and lower extremities, an upper conical section 23 which is comparatively long and tapers downwardly toward the throat and a lower conical section 24 which is comparatively short and flares downwardly from the throat and terminates at a distance from the bottom of the tank so as to form a lateral passage 25 between the lower end of the Venturi tube whereby communication is established between the interior of this tube at the lower end thereof and the annular space 26 intervening between the exterior of this tube and the wall of the tank.

In the preferred construction a base 27 rests on the bottom of the tank below the tube and is connected with the lower section of the same by a plurality of posts 28 arranged in an annular row, said lower tube section, base and posts being preferably cast in one piece of metal. The upper conical section is preferably made up of a vertical series of progressively larger conical elements 29 which are constructed of sheet metal and separated from one another by annular slots or circumferential openings 30, and a plurality of upright bars 31 of angle iron secured to the outer side of the several ele-

70

100

ments so as to connect them and hold them in spaced relation as a unit.

A short distance above the throat of the Venturi tube the upper section is divided along the transverse line 3—3 forming a lower fixed part 32 and an upper movable part 33 which is adapted to normally rest on the lower part 32 but can be raised to form a gap between the lower and upper parts 33, 32 through which liquid can pass for the purpose of continuing the mixing operation while emptying the mixing apparatus as will be more fully explained later on. The lower part 32 of the upper cone section of the Venturi tube is preferably cast integrally with the lower cone section, as shown in Fig. 1. The upper and lower cone sections 23 and 24 of the tube are retained in their proper relative position and the upper section is guided in its movements toward and from the lower section by guiding and retaining means consisting preferably of a plurality of upright guide pins 34 projecting upwardly from the lower tube section 24 on the exterior thereof and guide eyes 35 arranged on the exterior of the lowermost sheet metal unit of the upper tube section and each receiving the upper end of one of said guide pins, as shown in Figs. 1 and 3.

The numeral 36 represents a propeller whereby the liquid to be mixed is circulated through the Venturi tube and the tank, which propeller is arranged within the Venturi tube and preferably in line with the throat thereof and turned in the direction for causing the liquid to flow downwardly on the inner side of the tube and upwardly between the outer side of the tube and the tank. In the construction shown in Fig. 1 the base 27 is provided with an upwardly coned or dished central part 37 which carries an upwardly projecting pivot pin 38 on which the lower end of the hub 39 of the propeller is journaled.

Arranged centrally within the Venturi tube is an upright stirring shaft 40 which is secured at its lower end to the upper end of the hub of the propeller while the upper part of the shaft is journaled above this tube in a bearing 41 mounted on a cross piece 42 carried by means 43 on the upper end of the tank. Upward motion of the stirring shaft is prevented by a thrust collar 48 secured to this shaft and engaging with the lower end of the upper bearing 41, as shown in Fig. 1. Rotation of this shaft together with the propeller mounted thereon may be effected in various ways, for example by the means shown in the drawings consisting of a horizontal driving shaft 19 journaled in bearings 44 on the cross piece and receiving power from any suitable source, a bevel gear pinion 45 mounted on the driving shaft and meshing with a bevel gear wheel 46 secured to the upper end of the stirring shaft, and a

clutch 47 for connecting and disconnecting the driving shaft and driving bevel pinion.

Raising and lowering of the upper part of the Venturi tube for opening or closing a gap or passage between the same and the lower part of the tube immediately above the throat and propeller may be accomplished by a variety of means but those shown in Figs. 1, 2, 5 and 6 are satisfactory and constructed as follows:

The numeral 49 represents an upright guide sleeve surrounding the upper part of the stirring shaft and the collar 48 and depending from the lower end of the bearing 41 to which it is secured. On the upper end 75 of the Venturi tube the same has secured thereto a spider or openwork frame 50 the central part of which carries a guide-eye or hub 51 which is mounted on the guide sleeve 49 so as to be capable of sliding vertically 80 thereon and thus operate to keep the upper part of this tube centered relative to the stirring shaft as this part of the tube is raised and lowered. Along the side of the stirring shaft and guide sleeve is arranged a 85 horizontal hoisting or lifting shaft 52 which is journaled in suitable bearings 53 on the beams and adapted to be turned manually by a gear segment 54 secured to one end of this shaft, a worm 55 meshing with this segment, 90 a hand shaft 56 journaled in bearings 57 on the adjacent beam and carrying the worm, and a handle 58 on said shaft for manipulating the same, as shown in Figs. 2, 5 and 6. On opposite sides of the stirring shaft two 100 hoisting drum segments 59 are mounted on the hoisting shaft and to each of these hoisting segments one end of a hoisting line 60 is secured and adapted to be wound thereon, the opposite end of the respective line being 105 connected to the guide spider 50 at the upper end of the vertically movable part of the Venturi tube. Upon turning the drum segments in one direction or the other the upper part of the Venturi tube will be raised or 110 lowered for a purpose which will presently appear.

In the modified form of my invention shown in Fig. 9 the lower cone 61 of the Venturi tube is made of a steeper angle as compared with the relatively flat angle of the lower cone 24 in Fig. 1, and the lower end of the stirring shaft 62 is journaled on the pivot pin 38 instead of journaling the hub of the propeller thereon as in Fig. 1.

In a simplified form of my invention, as shown in Figs. 7 and 8 the upper and lower cones 63, 64 of the Venturi tube may be made more nearly equal in length with the lower 115 somewhat shorter than the upper, in which case the propeller 65 rotating in the throat 66 would be farther from the bottom of the liquid tank 67. This particular form of my invention also shows the upper and lower 120

cones of the Venturi tube immovable relatively to one another.

If desired, the Venturi tube 68 of this form may be mounted horizontally in the tank 69 and the propeller 70 may be operated by a 5 horizontal stirring shaft 71 extending to the exterior of the tank, as shown in Fig. 14.

When the apparatus is in operation the mixing of the liquid is effected in the manner which is illustrated in the diagrams shown 10 in Figs. 10-13 as follows:

The liquid to be mixed is let into the tank until the later is filled to a level high enough to submerge the Venturi tube and the top of the tank, and the upper part of this tube is 15 fully lowered when operating the machine so shown in Fig. 1.

Upon now turning the propeller of this 20 form by means of its driving mechanism the liquid is caused to flow in a general current which descends in the tube and raises outside of the tube and in this general current thus generated there are regular phases of eddy currents which are constantly in action. 25 These eddy currents may be divided into five main phases in which molecular turbulence occurs, these phases being located approximately in the various places or zones marked A, B, C, D, and E in the diagrammatic Figures 10, 11, 12 and 13. Referring now to 30 these last mentioned figures it has been found that in the zone A at the upper end of the Venturi tube the liquid to be mixed is given velocity by the action of the screw shaped propeller in the throat of the Venturi tube.

In this region or zone the progress of the liquid is from the annular volume between the Venturi tube and the tank and mixes at 35 the top of this tube before entering the same. The molecules converge to the center of the tube from every point of the tank circumference and merge or roll together as they dive 40 into the top of the Venturi tube.

When the liquid reaches the zone B in the 45 throat of the Venturi tube the propeller whirls the molecules and forces them downward at a velocity which is variable depending on the diameter of the tube and the speed of the propeller.

As the current of liquid issues from the 50 lower end of the Venturi tube the same is shot out in sharply defined radial curves in all directions forming phase or zone C at a maximum velocity toward the lower end of the 55 annular passage between the tube and the wall of the tank. As the current rises in the last mentioned passage the same divides into the phases D, E, of which the phase D curves upwardly along the inner side of the tank 60 wall and spreads its molecules fan-wise into a blend with neighboring currents which stream upwardly in vertical paths, while the series of eddy currents forming the phase E impinge at high velocity against the large 65 volume of liquid in the tank next to the con-

tracted part of the Venturi tube and thus effects a great but orderly turbulence in this region. The whole volume of liquid is thus set rolling and mixing in this particular zone so that part of the molecules flow downwardly 70 along the periphery of the lower conical skirt of the Venturi tube and mingle with the molecules projected laterally from the lower end of this tube and thus receive a fresh impetus from the current C. Finally the 75 liquid in the tank outside of the tube and above the throat of the same moves upwardly in vertical paths and passes radially inwardly from all directions to the phase A preparatory to beginning another cycle in the course 80 of circulating through the agitator.

A laboratory demonstration shows that the current velocity in the case of cement slurry was fixed at thirty feet per minute and excellent mixing is obtainable at even considerably 85 slower rate of motion. If, however, the current is too low it lacks the momentum to start the whole mass promptly through the cycle of phases after a prolonged shutdown.

At this velocity of thirty feet per minute 90 the screw propeller starts and establishes the cycle current in thirty seconds after shutdowns up to sixty-six hours of rest. The specific gravity of the slurry in the last instance registered 1.80, and the capacity of the 95 tank was ten and one-half gallons.

The consumption of electric current for operating the motor at 230 volts and 1720 R. P. M. for driving the propeller was as 100 follows:

Motor alone	0.440 amperes	
Motor and transmission	.680 amperes	
Motor, transmission and		
screw	.715 amperes	105
Used in mixing slurry	.034 amperes	
Used in mixing slurry	8.05 watts for 10½	
	gallons	
Used in mixing slurry	.76 watts per	
	gallon	110

It will, therefore, be noted that a very thorough mixture of the liquid is secured with the expenditure of comparatively little power.

In the most effective form of my invention 115 it has been found desirable to locate the throat of the Venturi tube as close as possible to the bottom, in fact so close that the propeller virtually scrapes the bottom of the tank and shoves the current directly out over the bottom as it issues from the lower end of the Venturi tube. By means of the apertures in the upper part of the Venturi tube it is possible to keep the propeller fully supplied with liquid even though the level of the same 120 reaches a very low position. When the level of the liquid is above the top of the Venturi tube most of the upstreaming liquid passes by the annular openings in the Venturi tube 125 and enters the upper or suction funnel of the 130

same so that the downflowing liquid in the same enters principally at the top thereof. When the liquid has been sufficiently mixed the same is drawn off from the tank and during this operation the propeller continues to 5 rotate to maintain the liquid in a mixed condition. As the liquid is drawn off and the liquid level drops below the top of the Venturi tube the liquid thereafter passes from the tank into the upper part of the Venturi tube through the annular openings therein and as the level of the liquid drops each of these openings is in turn uncovered by the liquid. When the level of the liquid drops 10 below the lowermost aperture, the flow of liquid from the tank through the Venturi tube to the propeller is obtained by raising the upper part of this tube by the lifting mechanism thereby supplying liquid directly to the propeller. When the level of the liquid sinks 15 below the upper fixed line of the throat and until the liquid level drops below the lower edge of the propeller, the latter exerts a violent beating action on the liquid whereby 20 the latter is thoroughly agitated and kept in a mixed condition until the tank is practically empty. During its operation the propeller shoots out an annular ring of liquid with sufficient force to overcome the specific 25 gravity of the heavy materials in the liquid so as to keep the bottom of the tank clear and not allow any heavy particles to settle there. The continued pressure of the propeller against the lower end of the column of liquid outside 30 of the Venturi tube causes this liquid to shoot upwardly in a violent state of turbulence which results in intimately mixing the ingredients in a minimum length of time, and thus effects a substantial saving in work of 35 this character.

When constructing the apparatus as shown in Fig. 1 in which the openings 30 are employed in the upper part of the Venturi tube at different levels thereof, these openings 40 should be made of the proper size so that normally the bulk of the liquid will pass upwardly on the outside of the tube to the top of the same and only a small quantity will enter this tube through these openings, thereby ensuring the longest path for most of the liquid 45 as it circulates through the machine and thus produces the most effective agitation of the same. Such liquid as may enter the tube through the openings 30 mingles with the descending stream in the tube and sets up addition turbulence which further expedites the mixing operation and produces a mixture of uniform consistency in less time than has been possible heretofore.

60 It will be noted that in Figure 1 the bearing for the lower end of the upright shaft 40 has an external downwardly flaring surface which leads from the upper reduced end of this bearing laterally to the openings at the lower end 65 of the mixing tube and that the hub 39 of the

propeller which is secured to the shaft also flares downwardly and that the lower edge of this hub overhangs the upper reduced end of the lower bearing.

By these means the propeller when turning for the purpose of forcing the current of liquid downwardly will tend to lift the driving shaft so that the liquid escaping through these lower openings will produce a suction or straining effect on the slight gap which will be present between the lower bearing of the shaft and the hub and thereby permitting only liquid to enter this space but preventing any solid material from entering the same so that wearing of the parts at this point and possible interference with the operation of the apparatus is prevented. This action of causing a suction on the joint between the lower shaft bearing and the hub of the propeller is further increased by the slight overhang of the propeller hub relative to the upper reduced end of the base portion of the bearing.

I claim as my invention:

1. An agitator comprising a tank, a double cone Venturi tube arranged within said tank and having an inflow section provided with an opening in its side and an outflow section, and a propeller arranged in said tube below 90 said opening.

2. An agitator comprising an upright tank, a tube arranged within the tank and having an intermediate throat, an upper conical inflow section tapering toward said throat and provided with inflow openings at different 95 points in its height and a lower outflow section which flares downwardly from said throat, and a propeller arranged within the throat of said tube.

3. An agitator comprising an upright tank, a Venturi tube arranged in said tank and having an intermediate throat, an upper inflow section tapering downwardly toward said throat and a lower outflow section flaring downwardly from said throat, said tube being 100 divided above said throat and the upper part thereof above said division being vertically movable, and a propeller arranged in said throat.

4. An agitator comprising an upright tank, a Venturi tube arranged within the tank and having an intermediate throat, an upper conical inflow section tapering toward said throat and provided with inflow openings at different 110 points in its height and a lower outflow section which flares downwardly from said throat, said tube being divided above said throat and the upper part thereof above said division being vertically movable, and a propeller arranged in the throat of the tube.

5. An agitator comprising an upright tank, a Venturi tube arranged in said tank and having an intermediate throat, an upper inflow section tapering downwardly toward said throat and a lower outflow section flaring 120

5 downwardly from said throat, said tube being divided above said throat and the upper part thereof above said divisions being vertically movable, a propeller arranged in said throat, and means for raising and lowering the upper part of said tube.

6. An agitator comprising an upright tank, a Venturi tube arranged in said tank and having an intermediate throat, an upper inflow section tapering downwardly from said throat, and a lower outflow section flaring downwardly from said throat, said tube being divided above said throat and the upper part thereof above said division being vertically movable, a propeller arranged in said throat, and means for raising and lowering the upper part of said tube, including a vertically swinging hoisting segment, and a line connected with the upper part of said tube and adapted to be wound on said hoisting segment.

7. An agitator comprising an upright tank, a Venturi tube arranged in said tank and having an intermediate throat, an upper inflow section tapering downwardly toward said throat, and a lower outflow section flaring downwardly from said throat, said tube being divided above said throat and the upper part thereof above said division being vertically movable, a propeller arranged in said throat, and means for raising and lowering the upper part of said tube, including a vertically swinging hoisting segment, a line connected with the upper part of said tube and adapted to be wound on said hoisting segment, a gear segment operatively connected with said hoisting segment, and a worm meshing with said gearment.

8. An agitator comprising an upright tank, a Venturi tube arranged in said tank and having an intermediate throat, an upper inflow section tapering downwardly toward said throat and a lower outflow section flaring downwardly from said throat, said tube being divided above said throat and the upper part thereof above said division being vertically movable, a propeller arranged in said throat, and means for guiding the upper part of said tube relative to the lower part thereof.

9. An agitator comprising an upright tank, a Venturi tube arranged in said tank and having an intermediate throat, an upper inflow section tapering downwardly toward said throat and a lower outflow section flaring downwardly from said throat, said tube being divided above said throat and the upper part thereof above said division being vertically movable, a propeller arranged in said throat, and means for guiding the upper part of said tube relative to the lower part thereof, including a plurality of guide pins projecting upwardly from said lower part, and a plurality of guide-eyes arranged on the upper part of said tube and receiving said guide pins.

10. An agitator comprising an upright tank, a Venturi tube arranged in said tank and having a contracted throat intermediate of its upper and lower ends, an upper section which tapers downwardly toward said throat and a lower section which flares downwardly from said throat, said upper section being provided with a plurality of annular slots arranged at different elevations in the height of the tube, and a plurality of upright bars secured to said upper section and extending across the slots thereof, and a propeller arranged in said tube.

11. An agitator comprising an upright tank, an upright Venturi tube arranged within the tank and having a reduced throat between its upper and lower ends, an upper section tapering downwardly toward said throat and an upper section flaring downwardly from said throat, said upper section being divided and forming an upper part which is movable vertically, a propeller arranged within the tube, an upright shaft arranged within the tube and carrying said propeller, a lower bearing which is arranged below the tube and on which the propeller is journaled, an upper bearing which is arranged above the tube and in which the upper part of said shaft is journaled, a collar on said shaft and engaging the lower end of said upper bearing, a guide sleeve surrounding the upper part of said shaft and depending from said bearing, a hub arranged on the vertically movable part of said tube and slideable on said guide sleeve, and means for raising and lowering said upper part of the tube.

12. An agitator comprising a tank, an upright tube arranged within said tank and having open upper and lower ends and having circumferentially extending openings in its side, and a propeller arranged within said tube.

13. An agitator comprising a tank, an upright mixing tube arranged within said tank and having open upper and lower ends, an upwardly tapering conical base arranged at the lower end of said tube and provided centrally on its upper small end with a pivot pin, a propeller arranged in the lower part of said tube and having a downwardly flaring hub which is journaled on said pin, and an upright shaft arranged in said tube and connected at its lower end with said hub and journaled at its upper end on said tank above said tube.

14. An agitator comprising a tank, an upright mixing tube arranged within said tank and having open upper and lower ends, an upwardly tapering conical base arranged at the lower end of said tube and provided centrally on its upper small end with a pivot pin, a propeller arranged in the lower part of said tube and having a downwardly flaring hub which is journaled on said pin, and an upright shaft arranged in said tube and

connected at its lower end with said hub and journaled at its upper end on said tank above said tube, the lower end of said hub being of larger diameter and extending laterally beyond the upper small end of said conical base.

15. An agitator comprising a tank, an upright tube arranged within said tank and having open upper and lower ends and provided with a plurality of circumferentially extending openings in its side at different points in the height thereof, and a propeller arranged within the tube.

10 In testimony whereof I, hereby affix my
15 signature.

HARRY J. SMITH.
